CYLINDER LOCK

John C. Bartho, Flushing, N. Y., assignor of one-half to Andre Tellier, New York, N. Y.

Application February 3, 1944, Serial No. 520,849

6 Claims. (Cl. 70—151)

This invention relates generally to locks and more particularly to the so-called Yale or cylinder type of lock.

In the ordinary Yale lock, the key is inserted for aligning the plunger pins in the cylinder in order to free the cylinder for rotation and then an additional turning of the key by the operator is necessary in order to turn the cylinder in order to retract the locking bolt. The door must then be pushed inwardly to open it. The additional turning movement of the key is often difficult, often necessitating the holding of the knob of the door with one hand and the turning of the key with the other hand, making it necessary to have both hands free which is not always the case.

Also in the ordinary Yale locks, the front or face of the plug member is exposed so that its movement may be seen and felt thereby assisting in the unauthorized manipulation of the lock.

Also in the ordinary lock of this type, a single rotatable cylinder is provided, which, while it affords a measure of security, is readily manipulated by a simple tool.

Furthermore in the ordinary locks, with which applicant is familiar, provision is made for opening the door from the inside of the door by turning a knob which retracts the locking bolt, but in order to hold the parts in open position it is necessary to slide a separate spring pressed latch member or finger piece into interlocking position with the moving parts of the lock. This holding mechanism adds to the expense of manufacture of the lock.

It is a primary object of my invention to simplify the legitimate key opening operation of the Yale type lock by eliminating the necessity for manual turning of the cylinder and by substituting therefor an automatic turning whereby the locking mechanism is moved to open position by the mere insertion of the key into the keyway of the cylinder and the door may be opened by merely pushing inwardly on the door.

Another object is to provide additional means of security by providing a second cylinder with plunger pins which must be manipulated before the locking mechanism is in position for opening.

A further object is to simplify the setting of the locking parts to open position from the inside of the door by providing means in common for moving the locking parts to open position and for holding said parts in moved open position.

In the drawings,

Fig. 1 is a view of a fragment of a door and door frame with a lock embodying my invention,

some of the parts being broken away for clearness.

Fig. 2 is a view of the locking mechanism in the casing with the cover removed and parts in section.

5 Fig. 3 is a sectional view taken on the plane of the line 3—3 of Fig. 2 and showing the sliding latch in projected latching position.

Fig. 4 is view similar to Fig. 3 but showing only part of the mechanism thereof and showing the latch in retracted position.

Fig. 5 is a sectional view taken through the door and locking mechanism, parts being shown broken away.

10 Fig. 6 is a sectional view taken on the plane of the line 6—6 of Fig. 5.

Fig. 7 is a sectional view taken on the plane of the line 7—7 of Fig. 5.

Fig. 8 is an exploded perspective view of the locking bolt and associated parts, parts being 15 broken away and parts being shown in section.

Fig. 9 is a detail view showing the camming device for holding the locking parts in open position.

Fig. 10 is a perspective view of modified 20 apparatus for holding the plunger pins against movement to prevent unauthorized manipulation of the lock.

My improved lock comprises a sectional casing or housing 10 fastened to a door 11 or the like 25 by screws 12 and a keeper or socket member 13 fastened to the frame of the door 14 by a screw 15.

Referring to Fig. 5 of the drawings, the door has a cut-out portion or recess 16 in which is 30 fittingly mounted a tubular housing 17 having an integral escutcheon plate 18 at its front positioned on the exterior of the door. Extending rearwardly of the plate 18 to the rear of the housing 17 and centrally thereof is an integral plug member 19. Positioned in the housing 17 above the plug 19 is a cylinder 20 and positioned below the plug 19 is a similar cylinder 21. Each cylinder is formed with a row of spaced recesses 22 in each of which is slidably mounted a plunger pin 23 urged outwardly of the recess by a coil 35 spring 24. The recesses in the cylinders are oppositely disposed.

The plug 19 is formed with an axially disposed keyway 25 which extends to the rear of the plug and communicates at the front thereof with a key 50 slot 26 formed in the plate 18. The upper wall of the plug, as viewed in Fig. 5, is formed with spaced openings 27 which communicate with the keyway 25, and with which the recesses 22 in the upper cylinder 20 are adapted to align. The lower wall of the plug is formed with spaced

openings 28 which communicate with the keyway 25 and with which the recesses 22 in the lower cylinder 21 are adapted to align. The aligned recesses and openings are adapted to receive the plunger pins 23.

The cylinders 20 and 21 are rotatable axially in the housing 17 and rotate in unison by means of a gear segment 29 fastened to the inner end of each cylinder and so positioned that their teeth 30 are continuously in mesh. The cylinders, plug and associated parts may be held in position in the housing 17 by a washer 31 screwed or otherwise fastened to the inner edge of the housing.

The casing 10 is fastened to the rear of the door and comprises an inner section 32 and an outer or cover section 33 in which are housed the locking bolt and mechanism for moving said bolt into and out of locking position and for holding said bolt out of locking position. This mechanism consists of a hollow post 34 extending centrally across the casing 10 and having its inner end projecting through an opening 35 in the floor of the inner section 32 and into the recess 16 in the door. The outer end of the post extends through an opening in the cover 33.

Fastened to the hollow post 34 is an annular cam member 36 having a peripheral hose portion 37. Also fastened to the post and spaced away from the cam 36 is a sleeve 38 and freely mounted on the post between said sleeve and cam is a washer member 39. This washer has an integral finger 40 projecting from the periphery thereof in one direction and an integral arm member 41 on its periphery projecting in an opposite direction, said arm terminating in a lug 42 which extends at right angles to the body of the arm. A collar 43 is secured on the end of the post and has a projection or lug 44 formed thereon.

The hollow post 34 and the elements fastened thereto are rotatably mounted and are urged to rotate by means of a spiral spring 45 which has one end fastened to a pin on the nose 37 of cam 36 and its other end fastened to the side wall of the inner casing section 32.

The locking bolt or latch member is indicated generally at 46 in Fig. 8 and comprises a body portion 47 and an integral extension 48 formed on one end of the body and disposed in a plane offset from the plane of said body. The extension is formed with a central slot 49 forming separate arms 50 and 51. Arm 50 terminates at its outer end in a lug 52 disposed at right angles to the plane of the arm in the direction of the body portion. On the free end of the other arm 51 is an elongated bar 53 extending at right angles to the arm 51 and also projecting slightly in the same direction as lug 52.

Pivottally mounted on the other end of the body portion 47 is a bolt member 55, so mounted on the pivot post 56 that its enlarged nose portion 57 projects outwardly of and forms an extension of the body portion. On the side of the bolt 55 opposite to the nose portion 57 is a projection or lug 58, which lug is normally positioned behind and in line with an opening 59 formed in the plane surface of the body 47.

The latching member or frame 46 is positioned adjacent the outer end of the hollow post 34, with its spaced arms 50 and 51 loosely straddling the outer end of the post, with the lug 52 on arm 50 projecting toward the cover of the casing.

A latching slide indicated generally at 60 in Fig. 8 is adapted to slide on the latching frame 46. This slide comprises a plate 61 formed with

an elongated slot 62 providing spaced arms 63 and 64. On the imperforate end of the plate is a rigid nose portion 65 which is offset from the plane of the body of the plate. A curved guide plate 66 is formed on the outer edge of each of the arms 63 and 64, and the outer end of arm 63 is formed with an enlarged offset portion 67. The arms 63 and 64 loosely straddle the hollow post 34 and slide on the arms 50 and 51 of the latching frame 46 guided by the curved plates 66 which partially encircle the arms 50 and 51, and the rigid nose 65 when in latching position is disposed behind the lug 58 on the pivotal bolt 55 thereby preventing movement of said bolt.

Extending centrally through the hollow post 34 is an elongated flat bar 68, the inner end of which is fastened to a projecting lug 69 fastened to the upper cylinder 20. In passing through the post, the bar passes through a slotted transverse wall 70 formed on the interior of the post, so that upon turning of the post the wall 70 turns the bar 68.

A knob or handle 71 is secured to the outer end of a spindle 72 which is journalled in the wall of the opening of the cover 33. The outer end of post 34 and the outer end of bar 68 extend into said spindle. The spindle 72 projects inwardly of the cover 33 and on its inner end adjacent said cover is fastened a cam member 73 formed with shoulders 74 on each side and an enlarged offset portion 75 centrally of said shoulders.

In using the lock, a key 76 with duplicate or opposite working faces is inserted through the key slot and into the keyway in the plug 49. The upper operating or working face of the key moves the upper plunger pins 23 outwardly or upwardly and the lower operating face moves the plunger pins in the lower cylinder 21 outwardly or downwardly simultaneously. Thus the plunger pins in the upper cylinder 20 are moved into alignment with each other and the plunger pins in the lower cylinder 21 are moved into alignment at the same time. When the pins are thus aligned the cylinders 20 and 21 are free to rotate. The spring 45 immediately goes into action turning the member 36 and associated parts including the hollow post 34 to which it is secured. Rotation of the post turns the bar 68 and this movement of the bar is transmitted to the upper cylinder 20 and turning of the upper cylinder is transmitted to the lower cylinder 21 through the intermeshing segments 29. Each cylinder is cut away as indicated at 20' to permit removal of the key after the cylinders are turned.

Upon the turning of the hollow post 34, the lug 44 on collar 43 is carried around into engagement with a pivoted pawl 77 and moves said pawl away from the inner end of bar 53 of latching frame 46, said pawl normally holding said frame against movement. The pawl is urged into holding position by a spring 78. The pawl may be manually moved out of engagement with the latching frame by a lever 79 fastened to one end of the pawl and extending to the exterior of the casing as seen in Fig. 2. When the pawl is thus moved away from the latching frame, said frame is free to slide.

The nose portion 37 of the cam member 36 is in interlocking engagement with a pin 80 on latching slide 60 and movement of said nose portion moves the slide and the rigid nose 65 out of latching engagement with the pivoted bolt lug 58. (See Fig. 4.)

All of the elements of the lock are now in condition for opening the lock and the door.

An inward push on the door causes the pivoted nose 57, which is now free to turn, to strike the keeper 13 and swing around and inwardly out of engagement with the keeper 13, opening said door. During this pivotal movement of the nose 57, the lug 58 swings into and through the opening 59 in the body 47.

When the door is thus pushed inwardly and the pivoted nose strikes the keeper 13 and is swung away from the keeper and the door rides free of the keeper, an elongated curved coiled spring 81 which has one end fastened to the inner wall of the lower section 32 of the casing and its other end fastened to a bolt 82 on the pivoted bolt 55, forces said pivoted bolt into normal projected position.

Now when the door is swung back or returned for closing, the pivoted bolt 55 being projected strikes the keeper 13 which causes the latching frame 46 and associated parts to slide inwardly. Upon inward movement of this frame, its inwardly extending bar 53 engages the finger 40 on the freely mounted washer 39 and simultaneously the nose portion 31 on cam 36 engages the opposite lug 42 on said washer, which engagement turns the hollow post 34 and associated parts including the long bar 68, which in turn moves the cylinders 20 and 21 bringing their recesses into alignment with the openings in plug 19 and thus permitting the plunger pins to assume their normal interlocking positions.

Continued closing movement of the door brings the pivoted nose beyond the striker portion of the keeper into alignment with the socket portion of the keeper at which time the coiled spring 81 forces the latching frame 46 outwardly. At the same time, a small coiled spring 83 which has one end fixed to the nose portion 31, as indicated at 84, and its other end fixed to the sliding latch offset portion 67 urges and forces said slide latch with its fixed nose 65 into interlocking position with the lug 58 on the pivoted nose 55.

The locking elements are now in locking position.

Provision is made for opening the door and lock from the inside. This is accomplished by first tilting the pawl 77 out of the way of the bar 53 of the sliding frame 46, by means of the lever 79. The knob 71 is then turned carrying the cam 73 around with it. This cam is so disposed that its shoulders 74 are opposed to the lug 52 and the outwardly projecting part of bar 53, and upon the turning of the cam one of its shoulders 74 engages either said lug 52 or projection 53 and slides the latching frame 46 inwardly moving the locking bolt or nose 55 away from the keeper 13 so that the door may be opened. Continued turning of said cam by means of the knob 71 will cause the engaging shoulder 74 to move around free of the engaged lug or projection and bring the offset central portion 75 of the cam into a position between and in engagement with said lug 52 and projection on bar 53. When the cam is in this position, the offset portion 75 holds the latching frame 46 against movement, holding the locking parts in open position.

In Fig. 10, mechanism is shown for preventing unauthorized manipulation or picking of the lock. In this modified form of lock, the plunger pins 85 are formed with grooves 86 in aligned relationship. A bar 87 is pivoted at one end to the plug so that one of its edges is adapted

to be swung into the aligned grooves of the pins to hold said pins against movement. The free end of the bar is formed with a cam nose portion 88, which cam portion is positioned in the path of movement of the key 89. Upon insertion of said key the entering edge of the key engages the cam portion 88 and moves it away from the plunger pins 85 permitting the key to move inwardly to align the pins as is usual. A spring 90 may be provided to urge the bar into interlocking position with the pins. By reason of this bar 87, it is impossible to reach the pins for manipulating them.

It will be noted that the pawl member 77 that holds the sliding locking bolt 46 from moving inwardly is positioned in the rear of the casing so that it will be impossible to reach it with a tool to pick it, and it would be futile to work on the pivoted nose of the lock to force it inwardly in view of the holding pawl.

It will also be noted that the cam member 73 which is used for opening the lock from the inside also serves to hold the part in open position.

It will also be noted that there are no movable parts on the escutcheon plate 18 which might be seen or felt as in the ordinary lock.

It will also be noted that it is not sufficient to pick the plunger pins in one cylinder but that such pins would also have to be picked in the other cylinder before the lock cylinders could be rotated.

I claim:

1. A cylinder lock including a rotatable cylinder, radially movable plunger pins in said cylinder, a plug having a keyway and openings for receiving said pins in interlocking position to prevent rotation of said cylinder, a key for moving said pins out of interlocking relationship upon insertion thereof into the keyway, a locking bolt operatively connected to said cylinder and means for automatically rotating said cylinder upon the movement of said pins out of interlocking position whereby said locking bolt is adapted to be moved out of interlocking position.

2. A cylinder lock including a rotatable cylinder, radially movable plunger pins in said cylinder, a plug having a keyway and opening for receiving said pins in interlocking position to prevent rotation of said cylinder, a key for moving said pins out of interlocking relationship upon insertion thereof into the keyway, a locking bolt operatively connected to said cylinder and spring actuated means for automatically rotating said cylinder upon the movement of said pins out of interlocking position whereby said locking bolt is adapted to be moved out of interlocking relationship.

3. A lock of the kind described, in combination, a rotatable cylinder, radially movable plunger pins in said cylinder, a plug having a keyway and openings for receiving said pins in interlocking relationship to prevent rotation of said cylinder, a key for moving said pins out of interlocking relationship upon the insertion of said key into said keyway, a rotatable post, spring means for urging rotation of said post, a locking bolt having a pivotally mounted locking nose portion, a slideable latch member having a nose portion in latching engagement with said locking nose portion and means of connection between said slideable latch and said rotatable post whereby upon movement of said pins out of interlocking position said post is rotated by said

70
75

spring means and moves the sliding latch out of latching engagement with said pivotal nose portion.

4. A lock of the kind described, in combination a rotatable cylinder, radially movable plunger pins in said cylinder, a plug having a keyway and openings for receiving said pins in interlocking relationship to prevent rotation of said cylinder, a key for moving said pins out of interlocking relationship upon the insertion of said key into said keyway, a rotatable post, spring means for urging rotation of said post, a locking bolt having a pivotally mounted locking nose portion, a slid-
able latch member having a nose portion in latching engagement with said locking nose portion, means of connection between said rotatable post and said rotatable cylinder whereby upon movement of said pins out of interlocking position said spring rotates said post and means of connection between said post and said pivotal bolt whereby upon movement of said post said sliding latch is moved out of latching engagement with said pivotal bolt to permit said bolt to pivot when moved into engagement with a stationary part of a door.

5. A lock of the kind described, in combination, a rotatable cylinder, radially movable plunger pins in said cylinder, a plug having a keyway and openings for receiving said pins in interlocking relationship to prevent rotation of said cylinder, a key for moving said pins out of interlocking relationship upon the insertion of said key into said keyway, a rotatable post, a spring device for urging rotation of said post, a locking bolt having a pivotally mounted locking nose portion, a slid-

able latch member having a nose portion in latching engagement with said locking nose portion, an elongated bar having one end fastened to said cylinder and its other end operatively connected to said rotatable post whereby upon movement of said pins out of interlocking position the said spring rotates said post, a cam member on said post and rotatable therewith and adapted to engage said sliding latch and move the latter out of latching engagement with said pivotal bolt to permit said bolt to pivot when moved into engagement with a stationary part of a door.

6. A lock of the kind described, in combination, a latching frame member having a pivotally mounted locking nose portion, a sliding latch for preventing pivoting of said locking nose portion, a spring actuated rotatable post adapted to move said sliding latch out of latching relationship with said locking nose portion and mechanism for preventing rotation of said post including a plug member having a keyway and oppositely disposed peripheral openings communicating said keyway, rotatable cylinders on opposite sides of said plug member, a gear segment fixed to each cylinder and in continuous mesh with each other, each cylinder having recesses adapted to be aligned with said openings and spring pressed plunger pins in said aligned recesses and openings for interlocking said plug and cylinders and being adapted to be moved out of interlocking positions by the insertion of a key into said keyway whereby said cylinders are permitted to rotate.
